UNITED STATES PATENT OFFICE

RALPH CAIAZZO, OF BROOKLYN, NEW YORK

DESIGN FOR A CIGAR PUNCH

Application filed January 31, 1930. Serial No. 34,358. Term of patent 14 years.

To all whom it may concern:

Be it known that I, RALPH CAIAZZO, a citizen of the United States, residing at Brooklyn, in the county of Kings, State of New York, have invented a new, original, and ornamental Design for a Cigar Punch, of which the following is a specification, reference being had to the accompanying drawing, forming part thereof.

In the drawings:

Fig. 1 is a front elevation; and
Fig. 2 is a bottom plan view.

I claim:

The ornamental design for a cigar punch as shown.

RALPH CAIAZZO.
